UNITED STATES PATENT OFFICE.

OTTO LEIGH, OF NEWARK, NEW JERSEY, ASSIGNOR TO UNGER BROTHERS,
OF NEWARK, NEW JERSEY, A CORPORATION.

DESIGN FOR A HANDLE FOR BUTTON-HOOKS OR SIMILAR ARTICLES.

SPECIFICATION forming part of Design No. 36,221, dated February 10, 1903.

Application filed June 28, 1901. Serial No. 66,441. Term of patent 3½ years.

To all whom it may concern:

Be it known that I, OTTO LEIGH, a citizen of the United States, residing at Newark, in the county of Essex and State of New Jersey, have ⁵ invented and produced a new, original, and ornamental Design for the Handles of Button-Hooks or Similar Articles, as Nail-Files, of which the following is a specification, reference being had to the accompanying drawing, ¹⁰ forming a part thereof.

The figure is a plan view of a handle for a button-hook or similar article, the body of a button-hook of conventional form being shown in dotted lines.

¹⁵ As shown in the drawing, the leading or material feature of my design consists of the raised scrolls 11, terminating in an apex between curved bands inclosing the spheroidal

bosses 22, above which the raised bands curve in opposite directions under and then ²⁰ upward and around the panel 3, terminating in the conventional representations of dolphin-heads 4 above the panel. The ornamentalations are in bold relief, as is indicated by the shading in the figure. ²⁵

Having thus described my invention, what I claim as new, and desire to secure by Letters Patent, is—

The ornamental design for the handle of a button-hook or similar article, as herein shown ³⁰ and described.

OTTO LEIGH.
